UNITED STATES PATENT OFFICE.

JOHN LOCKEN, OF COMSTOCK, MINNESOTA.

COMMUTATOR REAMER.

Application filed May 26, 1924. Serial No. 715,978.

This invention relates to a device for resurfacing the roller contacts of a commutator adapted for use in the well known Ford type of automobile.

An object of the invention is the provision of a simple, compact and unitary structure for clamping the commutator casing carrying the contacts and for reaming the surface upon which the usual roller brush for the commutator rides.

A further object of the invention is the provision of a device for not only clamping the casing carrying the spaced contacts of the commutator but for clamping the reamer to said casing in longitudinal alinement with the axis of the casing.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the appended claim.

In the drawings:

Figure 1 is a view in perspective of my improved reamer.

Figure 2 is a vertical section taken along the line 2—2 of Figure 3.

Figure 3 is a longitudinal vertical section of the reamer and clamping device.

Figure 4 is a view in perspective of the clamp and reamer in detached relation.

Figure 5 is a transverse vertical section taken along the line 5—5 of Figure 3.

Figure 6 is a transverse vertical section taken along the line 6—6 of Figure 3.

Referring more particularly to the drawings, 1 designates a standard or bracket adapted to be secured in any form of convenient socket clamp, or vise for supporting the cylindrical clamping member 2 in fixed position. The cylindrical member is split as shown at 3 and is provided with upstanding perforated lugs 4 and 5. The perforation of lug 4 is internally threaded to receive the threads of a bolt 6 formed integrally with a perforated head 7 which receives a slideable handle 8 for rotating the head and the screw. The inner end of the cylindrical member is provided with notches 8' adapted to receive the usual nuts and threaded studs 9 and 10 respectively, forming the binding

posts which are connected with the spaced metal arcuately shaped contacts 11 of the commutator casing 12. The contacts 11 are embedded in an insulating member 13 of ring formation which is secured in any approved manner to the inner wall of the casing 12.

The upper end of the bracket 1 is provided with a slot 14 adapted to receive a perforated projecting lug 15 secured to the casing 12 which is adapted to receive one end of an operating lever for rocking the commutator casing.

As shown more particularly in Figure 3, 70 the commutator casing 12 is inserted within the cylindrical member 2 and rigidly clamped by rotating the screw 6 and forcing the lugs 4 and 5 in close contact with each other. The outer open end 16 of the casing 75 12 projects sufficiently beyond the inner edge of the cylindrical clamping member 2 in order to permit the circular clamping ring 17 to telescope the projecting end of the casing. The ring 17 is split, as shown at 80 18 with the split ends provided with laterally projecting perforated lugs 19 and 20. The perforation of the lug 19 is provided with internal threads adapted to receive the threads of a screw 21 having a head 22 and operated by a sliding handle 23. When the screw is revolved lugs 19 will be drawn up tight with the split ends of the ring being rigidly clamped to the projecting end 16 of the casing 12.

The ring 17 is provided with converging arms 24 which are connected together by a bearing 25 for the shank 26 of a reamer 27. The reamer has cutting blades 28 on the enlarged head on the shank and the shank is slotted longitudinally at 33^a and bored as shown at 29 to receive a compression spring 30 and a rod 31 which has upon its outer end a frusto-conically shaped member 32 for forcing the split sections 33 of the reamer 100 apart when the nut 34 is drawn up upon the threaded end 35 of the rod 31. The screw engages the outer free end of the squared section 36 of the threaded end of the reamer. The compression spring 30 has one end in engagement with the inner face of the head 32 and its other end engaging the bottom of the bore 29. A disc 37 is placed in the bottom of the casing 12 and is engaged by the outer concave face 38 of the head 32 for maintaining the head in proper position upon the insulating ring 13 of the casing 12.

It will be noted that the reamer is split through the head 39 with the slots extending to the inner end of the bore 29 so that when the head 32 is drawn inwardly of the bore 29 the reamer section will be readily forced outwardly and in close contact with the inner surface of the insulating ring 13 and contacts 11.

After the casing 12 has been rigidly secured in the clamping member 2 and the split ring 17 has been clamped upon the projecting end 16 of the casing the nut 34 is adjusted for forcing the head 32 inwardly of the bore 29 and causing the blades 28 to rigidly engage the inner circular face of the insulating member 13. A handle having a square socket is placed upon the squared portion 36 of the shank of the reamer and revolves in a clockwise manner whereby the 20 blade will cut away the insulating member 13 and the surfaces of the contacts 11 and provide a true cylindrical surface for the roller brush to revolve upon.

By my improved reamer the surface of the contacts and the ring of insulating ma-

terial 13 may be re-surfaced as many times as may be desired which thereby eliminates the necessity of purchasing a new commutator each time it is found the contact surfaces are worn sufficiently to prevent proper 30 ignition.

What I claim is:

A device for reaming the interior of a shell comprising a split ring adapted to receive the shell, means for clamping the ring to the shell, converging arms formed integrally with the ring and terminating in a bearing sleeve coaxial with the ring, a reamer positioned within the ring and adapted to engage the shell said reamer having a stem embraced by the arms, said bearing sleeve forming a journal for said stem, a shoulder formed upon the stem in engagement with the arms where connected to the sleeve for limiting movement of the reamer in one direction, a stop plate for the reamer arranged in the shell, and cooperating means on the reamer and plate for retaining the plate in position in the shell.

JOHN LOCKEN.
